UNITED STATES PATENT OFFICE.

ARTHUR HENRY BLACKBURN, OF MATTEAWAN, NEW YORK.

AIR-HEATING DEVICE FOR GAS MAKING APPARATUS.

No. 924,033.

Specification of Letters Patent.

Patented June 8, 1909.

Application filed April 3, 1905. Serial No. 253,453.

To all whom it may concern:

Be it known that I, ARTHUR H. BLACKBURN, a subject of the King of Great Britain, residing at Matteawan, in the county of 5 Dutchess and State of New York, have invented certain new and useful Improvements in Air-Heating Devices for Gas-Making Apparatus, of which the following is a specification, reference being had to the drawings action 10 accompanying and forming part of the same.

The invention which forms the subject of my present application relates to apparatus for the manufacture of water-gas, in which the apparatus, consisting of generator, carbureter, and superheater, is from time to time 15 re-heated by passing therethrough a current of air, which, by supplying oxygen to the fuel in the apparatus causes the same to burn and so raise the temperature of the apparatus.

20 The object of my invention is to effect a saving of fuel by utilizing the waste heat of the apparatus to heat the air which is blown through the same.

Where cold air is blown through the apparatus 25 a considerable percentage of the heat developed by the combustion of the fuel is absorbed by the blast of cold air, which, having given up its oxygen, passes out of the superheater in a highly heated condition.

30 The heat thus carried off has heretofore been entirely wasted. I therefore propose to provide a system of pipes or other conduits in the path of the hot blast from the gas apparatus, and through the said system pass the 35 air which is to be delivered to the apparatus. By this arrangement a considerable part of the heat of the blast is given up to the air-heating system, and is absorbed by the air circulating therethrough, which, it will be re-

40 membered, is now delivered to the gas apparatus for the purpose of burning the fuel therein. The result is that, the air blast being highly heated instead of cold, it absorbs and carries away less of the heat produced by 45 this consumption of fuel and hence a greater proportion of the heat generated is effective to heat the apparatus. This effects a not inconsiderable saving of fuel.

50 My invention may be applied to practically any water gas plant, but in the accompanying drawings I have illustrated it applied to a plant of the well-known Lowe type.

55 In the drawing the figure shown is a side elevation, showing an air-heating system of a convenient form.

A, B, and C represent respectively, the

generator, carbureter, and superheater of a Lowe water gas plant. In the drawings two sets of apparatus is shown, and it is to be understood that so far as my invention is concerned any number of sets may be used. Immediately above each superheater is arranged a flue, D, leading to a casing E, within which is located an air-heater of any construction suitable for the purpose. In the construction herein specifically shown, the air heater, indicated in each case by F, consists of a plurality of vertical pipes connected to suitable upper and lower headers, the whole being so constructed and arranged that the air to be heated will pass successively through the various pipes of the system, so as to be exposed for a considerable time to the hot gases with which the heater is surrounded. For the purpose of forcing air through the heater 75 I provide any convenient form of blower, indicated by G, connected to the heater by a conduit H. The heated air is delivered from the heater through a conduit I, to a distributing pipe J, from which extend branches leading to the generators, carbureters, and superheaters, as shown. It will also be seen that the flue D in each case delivers products of combustion to the same air-heater, F, though it is of course 80 obvious that a separate heater may be provided for each set of apparatus if desired. Each flue D is also provided with a chimney, K, located immediately above and in line with the discharge-outlet, L, of the superheater, and provided with a damper, M, closing the lower end thereof, so that by turning the damper on its pivot communication with the heater-casing may be cut off and the products of combustion from the superheater 85 will then be discharged through the chimney K directly into the air. After passing through the heater-casing the products of combustion are delivered to the stack, N, and thence pass out into the air. 90

The operation of the apparatus described above will now be readily understood. When it is desired to blow air through the apparatus for the purpose of raising the temperature, the superheater discharge outlet is 105 opened and the blower, G, started. This drives the air through the heater, conduit I, and pipe, J, into the gas-making apparatus. The combustion of the fuel therein of course raises the various parts of the apparatus to a 110 high temperature, and the products of combustion issuing through the discharge outlet

of the superheater, are also highly heated. Being received by the flues, these hot gases are delivered to the casing surrounding the air-heater, and give up a large part of their 5 heat therein, thereby raising the temperature of the air which is passing through the heater to be later supplied to the apparatus. The result is that while the products of combustion thereafter may leave the apparatus at as 10 high a temperature as before, yet they do not carry off as large a proportion of heat, since when delivered to the apparatus the air which furnished the oxygen for the combustion of the fuel was already in a highly heated state; 15 or, stated otherwise, less fuel would be required to raise the apparatus to the desired temperature, since less of the heat of combustion will be taken up merely in heating the air introduced to support such combustion. 20

It will of course be understood that herein I have merely shown a convenient form of the apparatus constituting my invention, in a more or less diagrammatic way, preferring 25 to leave the working out of mere details to the skilled engineer who undertakes to install

the invention. I may state, however, that it is desirable, in order to utilize to the fullest extent the heat of the waste products of combustion, that the air-heating pipes should expose as large a superficial area as possible. 30

Having now described my invention what I claim is:

In a gas generating apparatus, the combination of a superheater, the latter having an 35 opening for the escape of heated gases, a chamber having an inlet opening in one side thereof, a conduit extending from said opening and having an open end arranged to receive products from the superheater, a valved 40 stack in said conduit located over the outlet of the superheater, an outlet from said chamber opposite to said inlet opening, a stack communicating with said outlet, an air conduit arranged in said chamber, means for 45 forcing air therethrough, and a conduit leading therefrom to the generator.

ARTHUR HENRY BLACKBURN.
